UNITED STATES PATENT OFFICE.

FRANK CARTLIDGE, OF CINCINNATI, OHIO, ASSIGNOR TO SULLIVAN MACHINERY COMPANY, A CORPORATION OF MASSACHUSETTS.

MINING MACHINE.

Application filed June 20, 1918, Serial No. 240,968. Renewed September 15, 1923.

This invention relates to mining machines, and especially to machines of the type adapted to cut either horizontal or vertical kerfs in a mine face, although, as will be seen, certain features thereof are by no means limited to machines of this particular type, but are capable also of use in connection with machines of other types, as, for example, machines for cutting horizontal kerfs alone, or those for cutting vertical kerfs alone.

The invention has for a general object the provision of improved means for positioning, supporting, guiding, operating, and controlling the cutting mechanism whereby the same is enabled to cut kerfs in a wide variety of planes, and whereby said mechanism is securely supported, accurately guided, and conveniently and reliably controlled during the cutting operation.

An important object of the invention is the provision of a truck mounted entry cutting machine adapted to cut a kerf in substantially the plane of the entry bottom, whereby the plane of said bottom may be maintained as the driving of the entry proceeds without supplemental shooting or other subsequent operation to remove the coal left upon said bottom by the cutter.

The foregoing and other objects of the invention, together with means whereby the same may be carried into effect, will best be understood from the following description of certain forms or embodiments thereof shown for purposes of illustration in the accompanying drawings.

In said drawings,—

Fig. 1 is a side elevation, Fig. 2 a plan view, and Fig. 3 a front elevation, partly broken away, of the complete machine.

Fig. 4 is an enlarged longitudinal vertical section taken substantially on the line 4—4, Fig. 2.

Fig. 5 is a detail horizontal section taken substantially on the line 5—5, Fig. 4.

Fig. 6 is a longitudinal vertical section, taken substantially on the line 6—6, Fig. 7, of the truck and guide with the cutting mechanism removed.

Fig. 7 is a plan view of the truck with the guide and cutting mechanism removed.

Fig. 8 is a detail view of the jack employed for bracing the cutting mechanism against lateral thrust.

Fig. 9 is a detail elevation of a portion of the clutch mechanism for controlling the swinging of the cutter bar.

Fig. 10 is a plan view partly broken away, showing a modified form of raising and lowering mechanism.

Fig. 11 is a detail elevation of a portion of the mechanism shown in Fig. 10.

Fig. 12 is a simplified diagrammatic plan view illustrating the operation of the machine in undercutting.

Fig. 13 is a simplified diagrammatic side elevation illustrating the operation of the machine in shearing.

Fig. 14 is a similar view showing the parts adjusted for transportation about the mine.

Fig. 15 is a similar view illustrating the operation of undercutting, and showing the manner in which the cutter is caused to operate substantially in the plane of the mine bottom.

Fig. 16 is a simplified diagrammatic plan view illustrating the operation of the machine in cutting a vertical kerf in a face located parallel to the track.

Fig. 17 is a similar view illustrating the operation of making a similar cut in the center of the end face of a mine entry.

Fig. 18 is a similar view illustrating the operation of the machine in making a similar cut in substantially the plane of a rib or side wall of the entry.

Fig. 19 is a simplified diagrammatic side elevation illustrating the operation of the machine in making an undercut in a plane inclined to the plane of the entry bottom.

Fig. 20 is a simplified diagrammatic end elevation illustrating the operation of the machine in making an inclined undercut in a face parallel to the track.

Fig. 21 is a sectional view on the line 21—21 of Fig. 7.

The invention is herein illustrated as embodied in a truck mounted machine equipped with a cutter bar and an endless cutter chain of the type now ordinarily in use in coal cutting machines, and provided with improved means whereby said cutter bar may be adjusted into various operative positions to insert an undercut or to cut a vertical kerf, all while the cutting mechanism is maintained upon the truck.

Referring to Figs. 1 and 2, the machine includes a truck frame 25 mounted on wheels

26 adapted to run upon the usual trackway 27. As illustrated, the truck is preferably adapted to be propelled about the mine under its own power and to this end the axle 5 of one pair of wheels 26 is connected by chain and sprocket gearing 28 with a shaft 29 journaled in the truck body 25 and provided with a worm gear 30 (see Fig. 6) meshing with a worm 31 on the shaft 32 of an 10 electric or other motor 33. Preferably, the motor 33 is of the reversible type and is controlled by a suitable controller 34. The worm 31 is preferably loosely mounted on the shaft 32 and may be connected therewith 15 by means of a suitable clutch 35. Thus it will be seen that by proper operation of the controller 34 and clutch 35, the truck may be propelled about the mine at will under its own power and in either direction, or may 20 remain stationary.

Carried upon the truck frame 25 is a supplemental supporting frame or turntable 36 disposed in a plane substantially parallel to the plane of the track 27 and truck frame 25, but mounted on the latter for angular and vertical movement with respect thereto. To this end, the truck frame 25 is formed with a cylindrical chamber or guide 37 which receives a depending cylindrical flange 38 bolted or otherwise secured to the frame 36, said flange 38 substantially fitting and telescoping with the guide 37 and being preferably braced by suitable radial ribs 39. The flange 38 is adapted to turn within the 30 guide 37, thereby permitting the frame 36 to be adjusted into substantially any angular position with respect to the truck body 25 and trackway 27.

For raising and lowering the frame 36 with respect to the truck, there is provided a hydraulic motor, ram, or jack comprising a cylinder 40 arranged concentric with the guide 37 within the same, and a piston 41 within said cylinder and abutting, at its 45 upper end, the lower side of the frame 36. The cylinder 40 is preferably formed integral with the guide 37 and is provided at its under side with a removable head 42. The piston 41 may be provided with packing 43 of any suitable form. The cylinder 40 is supplied with pressure fluid through a passage 44 in the bottom wall of the guide 37, said passage communicating with a pipe 45 leading from the discharge valve 46 of a 50 pump comprising a plunger 47 operating in a cylinder 48. The pump cylinder 48 is provided with the usual inlet valve 49 communicating with a reservoir 50 for oil or other liquid, said reservoir being 55 preferably formed integral with the guide 37. The operation of the piston 41 in the cylinder 40 is controlled by a suitable valve 51 interposed between the pump cylinder 48 and the discharge valve 46, 60 and communicating also with the reservoir

50, said valve being preferably of the three-way type and operable to admit pressure from the pump cylinder 48 to the ram cylinder 40, to trap liquid in said ram cylinder, or to discharge said liquid into the reservoir 50. Valves of this type being well known in the art, this valve is not illustrated in detail herein, as, specifically, it forms no portion of the present invention. 70

The pump plunger 47 is connected by a pitman 52 with a crank disk 53 (see Fig. 7) on a shaft 54 journaled in suitable bearings on the truck frame 25, said shaft being provided with a worm gear 55 meshing with a worm 56 loosely mounted on the motor shaft 32. The clutch 35 is preferably double acting, and is adapted to connect either of the worms 31 or 56 to the shaft 32, or to occupy a neutral position in which both of said worms are disconnected from said shaft, 80 whereby the power of the motor 33 may be employed at will either to propel the truck or to raise the frame 36 by means of the hydraulic ram 40, 41. 85

Mounted on the turntable or supporting frame 36 for tilting movement about a transverse horizontal axis, is a carriage or guide 59 having a pair of parallel ways 60 provided, respectively, with trunnions 58 which are received in bearings in uprights 57 carried by said frame 36. The guide 59 with its ways 60 may be angularly adjusted with respect to the frame 36 about the axis of the trunnions 58 by means of an adjusting screw 61 pivoted at 62 to a cap plate 63 bolted or otherwise secured to the frame 36, said screw cooperating with a nut 64 rotatably secured, as by suitable gibbs 65, to the guide 59 and provided with a suitable hand wheel 66. 100

Mounted in the ways 60 for movement longitudinally thereof, is the cutting mechanism including a reversible electric or other motor 67 having a suitable controller 67^a (Figs. 1 and 2), a cutter bar 68 carrying the usual endless chain 69 provided with cutter bits 70, and connections hereinafter more fully described for supporting, positioning, and operating the cutter bar and for actuating the cutter chain. 110

Mechanism is provided for moving the cutting mechanism above referred to longitudinally in the ways 60 in either direction, said mechanism, as herein shown, in Figs. 1 and 2 being as follows: The shaft 71 of the motor 67 is provided with a bevel pinion 72 which meshes with a bevel gear 73 on an upright shaft 74 journaled in an extension 75 on the motor frame. The shaft 74 is provided with a worm 76 which meshes with a worm gear 77 on a shaft 78 journaled in uprights 79 on the extension 75. Loosely mounted on the shaft 78 is a pair of spur gears 80 and 81 having clutch faces adapted to be engaged by a clutch hub 82 operated 120

by a suitable clutch lever 83, whereby said clutch hub may be operatively engaged with either of the gears 80 or 81 to connect the same to the shaft 78, or may be moved into a neutral position in which both of said gears are disconnected from said shaft. The gear 80 meshes with a gear 84 on a shaft 85 extending parallel to the shaft 78 and also journaled in the uprights 79. The gear 81 meshes with a pinion 86 which in turn meshes with a gear 87 also on the shaft 85. By moving the clutch hub 82 to connect the gear 80 with the shaft 78, the shaft 85 will be driven from said shaft 78 in one direction 10 by the gears 80 and 84, while by operating the clutch hub 82 to connect the gear 81 with the shaft 78, the shaft 85 will be driven in the opposite direction through the gears 81, 86, and 87. The shaft 85 carries at its ends 15 pinions 88 which mesh with racks 89 formed on the ways 60, whereby as the shaft 85 is rotated in one direction or the other the cutting mechanism will be fed forwardly or backwardly in said ways, said pinions serving also as roller supports for the rear end 20 of the motor casing upon the ways 60.

A modified form of mechanism for raising and lowering the guide 59 relative to the truck, capable of use in substitution for the 25 hydraulic ram above described, is illustrated in Figs. 10 and 11. As shown in said figures, a shaft 90 is rotatably mounted in suitable bearings in the ways 60, said shaft being provided with a gear 91 adapted to be engaged by the gear 87 when the cutting mechanism is in its rearmost position in said ways. The shaft 90 is provided at its ends with worms 92 which cooperate with worm gears 30 93 on shafts 94 extending parallel to the ways 60 and journaled in suitable brackets 95 secured thereto. Upon each end of each of the shafts 94 is a pinion 96, said pinions meshing with racks 97 formed on uprights 98 rising from the turntable or supporting 35 frame 36. Cooperating with the uprights 98 are gibbs 99 secured to the ways 60, whereby the carriage 59 is guided for vertical movement on said ways. The walls of the uprights 98 are formed with slots 100 through 40 which the shafts 94 extend, said slots permitting the vertical movement above referred to. The gear 91 is loosely mounted on the shaft 90 but may be operatively connected thereto by means of a friction clutch 101 operated by a clutch controlling lever 102, and in this form of the invention the gear 87 is also loosely mounted on its shaft 85 and is operatively connected therewith by means of a clutch hub 103 operated by a clutch controlling lever 104. By proper operation of the clutches 101 and 103 and of the motor controller 67^a (which governs the direction of rotation of the motor), the mechanism can be so adjusted as to cause 45 the carriage 59 to be raised or lowered, or

to cause the cutting mechanism to be fed forwardly or backwardly in the ways 60.

Referring to Fig. 4, the casing of the motor 67 is formed at its forward end with a vertically disposed disk 105 having a peripheral flange 106 upon which is guided, for rotary movement about an approximately horizontal longitudinal axis, the annular rear end 107^a of a casing or turret 107 carrying the cutter bar and certain of the transmission mechanism for actuating the same. The forward end of the casing or turret 107 is provided with a trunnion 108 which is journaled in a yoke 109 secured at its rear end to the casing of the motor 67, and provided adjacent its forward end with rollers 110 engaging the ways 60, whereby the forward end of said turret is supported and said turret rendered free to rotate about a longitudinal axis without imposing eccentric strains upon the annulus 107^a and guide disk 105 by which the rear end of said turret is rotatably supported from the motor casing. For so rotating the turret 107, said turret has secured thereto a segmental rack 111 with which cooperates a pinion 112 fixed upon the forward end of a shaft 113 journaled in suitable brackets 113^a on the casing of the motor 67, said shaft having fast upon its rear end a worm gear 114 (Figs. 1 and 2) 50 cooperating with a worm 115 on a shaft 116 journaled in suitable bearings 116^a on the motor casing, said shaft having on its end a gear 117 which meshes with a gear 118 loosely mounted on the shaft 78 but adapted to be connected therewith by means of a friction clutch 78^a controlled by a suitable clutch lever 78^b.

Mounted upon the turret or casing 107 for rotation about an axis transverse to the axis of rotation of said turret 107, is a second turret or casing 119 (Fig. 4). Said turret 119 comprises a flat cylindrical portion 119^a, a sleeve portion 119^b, and an outer or lower head portion 119^c, said portions being preferably connected by a strengthening web 119^d. The cylindrical portion 119^a has bolted or otherwise secured thereto a ring or annulus 120 which engages an annular guide surface or flange 121 on the turret 107, while the sleeve portion 119^d is rotatably mounted on a similar sleeve portion 119^e of the turret 107. To facilitate the assembly of the parts, the flange 106 and annulus 107^a are cut away, as at 119^f, leaving an opening through 55 which the cylindrical portion 119^a may be passed when the sleeve portion 119^b is slipped over the sleeve portion 119^e. The cutter bar 68 is carried by a casting 68^a bolted or otherwise secured within the head portion 119^c. The sleeve portions 119^b and 119^e are of such a length that the cutter bar 68 is offset from the axis of rotation of the turret 107 a distance which is greater than 60 one-half the outside horizontal width of the 130

ways 60, so that by rotating the turret 107, as above explained, the cutter bar may be swung upwardly from the horizontal position shown in Figs. 1 to 4 into a vertical position at one side or the other of the ways 60 and beyond or outside the same, as shown, for example, in Figs. 16, 17, and 18.

The motor shaft 71 is journaled at its forward end in a bearing 122 located in a suitably disposed opening in the guide disk 105, said shaft having secured to its forward end a pinion 123 which meshes with a gear 124 fast on a hollow shaft 125 coaxially disposed with respect to the turret 107 and journaled in suitable bearings therein. The shaft 125 carries at its forward end a bevel pinion 126 which meshes with a bevel gear 128 on a shaft 129 journaled adjacent its upper end in suitable bearings in the turret 107, passing through the sleeve portions 119^b and 119^c, and journaled at its lower end in a bearing 130 in the turret 119, said shaft being coaxially disposed with respect to the latter turret. Rotatably mounted on a sleeve 131 fixed to the shaft 129 adjacent its lower end is a sprocket 132 for actuating the cutter chain 69, said sprocket being adapted to be connected with the shaft 129 for rotation therewith by means of a clutch hub 133 connected by links 134 with a clutch controlling ring 135 operable from the exterior of the turret or casing 107 by means of suitable clutch controlling handles 136 (Fig. 3).

For turning the turret 119 upon its axis 35 to swing the cutter bar 68 about said axis, the following mechanism is provided: The cylindrical portion 119^a of the turret 119 is formed with an internal gear or rack 138 with which meshes a pinion 139 on the end 40 of a shaft 140 journaled in a suitable bearing 137 in the turret 107. Fast upon the shaft 140 is a worm gear 141 which meshes with a worm 142 on a shaft 143 journaled in suitable bearings in the turret 107. The shaft 143 has fast upon its opposite ends large and small gears 144 and 145, respectively, (see Fig. 5) which mesh with small and large gears 146 and 147 loosely mounted on a shaft 148, also journaled in suitable 50 bearings in the turret 107, and adapted to be alternatively clutched thereto, as by clutch hubs 149 and 150, whereby the shaft 143 may be operatively connected with the shaft 148 for relatively fast and slow rotation, or 55 may be operatively disconnected therefrom. The clutch hubs 149 and 150 are carried by a yoke 151 connected to a slide 152 (Fig. 4) guided in a cap plate 153 in the turret 107, said slide 152 being movable to operate said 60 clutch hubs by means of an arm 154 on a shaft 155 coaxially disposed within the shaft 125 and journaled therein and in a bushing 156 carried by the turret 107. For convenience in assembling, the shaft 155 is preferably 65 formed in two separable parts connected by

a clutch or coupling 157. At its end, the shaft 155 carries a bevel gear 158 which meshes with a bevel gear 159 on a shaft 160 journaled in suitable bearings and carrying at its opposite end a bevel gear 161 (Fig. 9) 70 which meshes with a bevel gear 162 on an upright shaft 163 journaled in the motor casing and provided at its end with an operating handle 164 (Figs. 1 and 2). The shaft 148 has fast thereon a worm gear 165 75 (Figs. 4 and 5) which cooperates with a worm 166 loosely mounted on the shaft 129 but normally connected therewith by a yielding device or "friction" 167 such as is usually employed in machines of this character to 80 prevent damage to the parts under conditions of overload. The friction device herein shown is of a type well known in the art and, as, specifically, it forms no portion of the present invention, will not be described in detail herein.

The machine herein described may be employed in the operations of entry driving either for the purpose of undercutting or for the purpose of making vertical or shear 90 cuts. In either event, the machine is propelled under its own power to the end of the entry, and of the trackway therein, until the ends of the ways 60 are brought into engagement with the face to be cut, said ways 95 being thereupon secured to the face, as by means of spurs 168 carried thereby. If desired, said ways may be further provided with jacks 169 (Figs. 13, 14, and 15) adapted to engage at their opposite ends the mine 100 face and roof, respectively. The ends of the ways 60 may, therefore, be securely supported by the mine face without interference with the free operation of the cutter bar upon said face beneath said ways. If desired, the truck may be securely anchored in place by means of short jacks 170 (Figs. 12 and 13) pivotally connected to the truck body 25 and adapted to engage the mine 105 bottom between the rails of the trackway 27 110 or adjacent thereto.

In the operation of undercutting, the turret 107 being in the position shown in Figs. 1 and 4, with the cutter bar horizontal, the turret 119 is rotated to swing the cutter bar outwardly into the position indicated by the letter A in Fig. 12. The cutting mechanism is then fed forwardly in the ways 60 to carry the cutter bar into the position B shown in Fig. 12, thereby making the summing cut. 115 The turret 119 is then swung to carry the cutter bar from the position B to the position C; and the cutting mechanism is finally moved backwardly in the ways 60 into the position D to complete the cut, all in accordance with a well known method of undercutting. It will be observed in this connection that the transmission connections 80, 81, 82, etc., permit the direction of movement of the cutting mechanism in the ways 120 125

60 to be reversed without reversing the motor 67 and consequently the direction of travel of the cutter chain, so that the latter continues to cut throughout the rearward as 65 well as the forward movement of the cutting mechanism. In order to resist turning of the turret 107 on its axis due to the reaction or thrust of the eccentrically carried or offset cutter bar during its cutting operation, an 70 10 auxiliary jack 171, shown in detail in Fig. 8, may be employed. Said jack preferably comprises two relatively extensible parts in threaded engagement with one another, one of said parts being provided with a yoke 172 15 adapted to embrace the sleeve portion 119^b of the turret 119, and the other of said parts carrying at its end a spur 174 adapted to engage the rib or side wall of the entry. 20

In the operation of shearing, which is 25 diagrammatically illustrated in Fig. 13, the turret 107 is rotated to swing the cutter bar upwardly into a vertical position at one side or the other of the ways 60, whereupon the mechanism may be operated, substantially as 30 above described in connection with undercutting, to produce a vertical cut.

It will be seen that the entire cutting mechanism, and especially the cutter bar, is supported or suspended beneath its guides 35 or ways 60. By virtue of this underslung arrangement, several important advantages are obtained. For example, and as above explained, the guides 60 may be securely supported at their ends by the mine face being 40 cut, by either the spurs 168 or jacks 169, or both, thereby providing firm supporting and guiding means for the cutting mechanism in close proximity to the face. Also, as above explained, the cutter bar may be swung upwardly from its horizontal position in either direction into a vertical position at either side of the ways 60 and beyond the same, thereby permitting said cutter bar to swing 45 freely in either one of two vertical planes without interference therewith by said guides. In this manner a vertical cut may be inserted in either one of two planes oppositely located with respect to the trackway. For example, if the trackway be located 50 nearer one side than the other of the entry, as is frequently the case, the cutter bar may be employed to cut a vertical kerf substantially centrally of the entry, as shown in Fig. 55 17, or may be employed to cut a kerf in substantially the plane of the adjacent side wall or rib, as shown in Fig. 18, thereby insuring a straight rib.

Perhaps the most important advantage of 60 the apparatus due to its underslung arrangement together with the provision for vertically adjusting the cutting mechanism, resides in the ability of the machine to cut squarely upon the mine bottom, that is to say, to make an undercut in a plane substantially 65 coincident with the plane of the mine bot-

tom. In the truck mounted entry driving machines heretofore generally used, it has been impossible to insert an undercut below the surface of the rails of the trackway upon which the truck travels. As a result, the 70 undercut is usually made some six or eight inches above the entry bottom, so that, after shooting the coal, a layer (amounting approximately to a ton for each cut) remains 75 upon the mine bottom and must be removed by hand, as by a special gang of men with picks, before the cutting can proceed. It will be seen, however, that with the present machine the hydraulic ram can be operated to elevate the cutter bar into a position 80 above the tops of the rails, as shown in Fig. 14, thereby permitting the machine to be transported from place to place about the mine without interference with the rails by the cutter bar, but that when the end of the 85 trackway is reached, as shown in Fig. 15, the elevating mechanism may be released to permit the cutter bar to rest squarely upon the bottom, so that, when operated in the manner above described, and as illustrated 90 in Fig. 12, said cutter bar will produce an undercut such that, when the superimposed coal is broken down, the operation is complete, and there is no necessity of removing 95 any coal from the mine bottom in order to maintain the plane of the latter.

Should it be desired, for any reason, to undercut the end face of the entry upon an inclination to the plane of the bottom previously established, as in avoiding an obstruction, or in following a pitching seam, the machine may be adjusted as shown in 100 Fig. 19, the elevating mechanism being operated to such an extent as may be necessary, and the hand wheel 66 manipulated to incline the guides 60 at any desired angle with 105 respect to the trackway.

In addition to its operations upon the end face, as in entry driving, the machine is also capable of either shearing or undercutting 110 a face disposed parallel to the trackway, as in opening a room neck. The operation of inserting a shear cut in such a face is illustrated in Fig. 16. To adjust the machine for this purpose the turntable or supporting frame 36 is turned about the axis of the cylindrical guide 37 in a direction to carry the forward ends of the guides 60 into engagement with the wall to be cut, after 115 which the mechanism may be operated as 120 above described in connection with entry driving. While the mechanism is illustrated in Fig. 16 as adjusted for the purpose of shearing, it is obvious that, by suitably rotating the turret 107, the mechanism may be 125 adjusted to produce an undercut in a side face in the same manner as above described in connection with the end face. Where the side face or wall to be cut is in close proximity to the trackway, the mechanism may 130

be adjusted into the position shown in Fig. 20, that is to say, the turret 119 may be rotated upon its axis to cause the cutter bar to extend laterally with respect to the trackway and to swing said cutter bar through any desired arc at the side of said trackway. If it be desired to insert the undercut at an angle to the plane of the trackway, the turret 107 may be suitably rotated in order to bring the cutter bar into the desired plane, the parts being shown as so adjusted in Fig. 20.

While I have in this application specifically described certain forms which my invention may assume in practice, it will be understood that these forms of the same are shown for purposes of illustration and that the invention may be modified and embodied in various other forms without departing 20 from its spirit or the scope of the appended claims.

What I claim as new and desire to secure by Letters Patent is:

1. In a mining machine, the combination 25 with a guide disposable substantially against a face in which a kerf is being cut and a truck mounting therefor relative to which said guide is normally longitudinally extending and upon which said guide is adjustable while maintaining the plane thereof parallel to a horizontal line extending longitudinally of the guide, of cutting mechanism movable on said guide longitudinally thereof, said cutting mechanism being supported by said guide and being located beneath the same and being disposable substantially midway between the sides of said guide when the latter is in substantial abutment against the face.
2. In a mining machine, the combination 40 with a guide disposable substantially against a face in which a kerf is to be cut and a truck mounting therefor relative to which said guide is normally longitudinally extending and upon which said guide is adjustable while maintaining the plane thereof parallel to a horizontal line extending longitudinally of the guide, of cutting mechanism movable on said guide longitudinally thereof, of said cutting mechanism being suspended beneath said guide and including a swinging cutter bar disposable substantially midway between the sides of said guide when the latter is in substantial abutment against the face.

3. In a mining machine, the combination 60 with a vertically rectilinearly movable normally longitudinally extending guide disposable substantially against a face in which a kerf is to be cut, of cutting mechanism movable on said guide longitudinally thereof, said cutting mechanism being supported by said guide and being located beneath the same and being disposable substantially midway between the sides of said guide

when the latter is in substantial abutment against a face.

4. In a mining machine, the combination 70 with a vertically rectilinearly movable normally longitudinally extending guide disposable substantially against a face in which a kerf is to be cut, of cutting mechanism movable on said guide longitudinally thereof, said cutting mechanism being suspended beneath said guide and including a swinging 75 cutter bar disposable substantially midway between the sides of said guide when the latter is in substantial abutment against a face.

5. In a mining machine, the combination 80 with a laterally pivotable normally longitudinally extending guide engageable with the face, of cutting mechanism including a pivoted elongated cutter bar and including supporting means adjustable merely by 85 swinging about a horizontal axis to position said bar and its pivot substantially equal amounts beyond said guide at either side thereof while said guide remains stationary.

6. In a mining machine, the combination 90 with a laterally pivotable normally longitudinally extending guide engageable with the face, of cutting mechanism movable in said guide and longitudinally of the latter, 95 said cutting mechanism including a cutter bar and being adjustable merely by swinging about a horizontal axis to position said cutter bar substantially equal amounts beyond said guide at either side thereof and 100 parallel to the latter while said guide remains stationary.

7. In a mining machine, the combination 105 with a laterally pivotable normally longitudinally extending guide engageable with the face to be cut, of cutting mechanism movable on said guide longitudinally thereof, and including a cutter bar and means for supporting said bar on said guide beneath the latter and permitting swinging of said 110 bar across the front end of said guideway and adjustable to position said bar as a whole substantially equal amounts beyond the guide at either side of the latter without movement of said guide.

8. In a mining machine, the combination 115 with an approximately horizontally disposed guide, of cutting mechanism movable in said guide longitudinally thereof, said cutting mechanism including a turret rotatable about an axis extending longitudinally of said guide and a cutter bar carried by said turret and offset from said axis, whereby said cutter bar may be positioned beyond said guide at either side thereof, 120 said cutting mechanism being movable in said guide to a position in which said cutter bar lies substantially wholly in the rear of the front end of said guide.

9. In a mining machine, the combination 125

- with an approximately horizontally disposed guide, of cutting mechanism movable on said guide longitudinally thereof, said cutting mechanism being suspended beneath 5 said guide and including a turret rotatable about an axis extending longitudinally of said guide, and a swinging cutter bar carried by said turret and offset from said axis whereby said cutter bar may be positioned 10 to swing in planes outside said guide at either side thereof, said cutting mechanism being movable on said guide to a position in which the axis of swinging movement of said cutter bar is to the rear of the forward 15 end of said guide.
10. In a mining machine, the combination with an approximately horizontally disposed guide, of cutting mechanism movable in said guide longitudinally thereof, said cutting 20 mechanism including a turret rotatable about an axis extending longitudinally of said guide and a cutter bar carried by said turret and offset from said axis, said turret being movable to position said cutter bar in 25 a vertical plane outside said guide at either side thereof and said cutting mechanism being disposable in said guide in a position in which the rear end of said bar is substantially to the rear of the front end of said 30 guide.
11. In a mining machine, the combination with a guide, of kerf cutting mechanism including a swinging cutter chain carrying 35 cutter bar movable on said guide longitudinally thereof, and means for supporting the forward end of said guide from the face being cut.
12. In a mining machine, the combination with a guide, of kerf cutting mechanism including a swinging cutter chain carrying 40 cutter bar movable on said guide longitudinally thereof, said cutting mechanism being supported by said guide and being located beneath the same, and means for supporting the forward end of said guide from the face being cut.
13. In a mining machine, the combination with a guide and means for supporting the forward end of said guide in the face being 45 cut, of cutting mechanism movable in said guide longitudinally thereof, said cutting mechanism including a cutter bar and being adjustable to position said cutter bar beyond said guide at either side thereof.
14. In a mining machine, the combination with a guide, of kerf cutting mechanism including a swinging cutter chain carrying 50 cutter bar movable on said guide longitudinally thereof, said guide having a projecting portion adapted to engage the mine face to support said guide.
15. In a mining machine, the combination with a guide, of cutting mechanism movable in said guide longitudinally thereof, and a 55 double pointed jack carried by said guide at its forward end, said jack being adapted to engage the mine roof and face at its opposite ends, respectively.
16. In a mining machine, the combination with cutting means including a chain carrying cutter bar pivotally mounted for swinging movement in intersecting planes and an actuating motor therefor whose axis of rotation is parallel to the planes of the bar, of means for supporting said cutting means, 70 said supporting means being vertically rectilinearly movable and being adjustable about a transverse horizontal axis. 75
17. In a mining machine, the combination with a guide and cutting mechanism longitudinally movable in said guide during cutting and pivotally mounted for swinging movement, of means for moving said guide vertically, and means for tilting the same about a transverse horizontal axis. 80
18. In a mining machine, the combination with a guide, of cutting mechanism movable on said guide longitudinally thereof during cutting, said cutting mechanism comprising a pivoted cutter bar and being supported by 85 said guide and being located beneath the same, means for moving said guide vertically, and means for tilting the same about a transverse horizontal axis. 90
19. In a mining machine, the combination with angularly adjustable cutting mechanism including a cutter movable in planes substantially parallel to the axis of adjustment of said cutting mechanism and offset therefrom, of a jack engaging said cutting 95 mechanism for holding the same against angular movement about said axis when said cutter is in operation.
20. In a mining machine, the combination with a guide and means for supporting the forward end of said guide in the face being 100 cut, of cutting mechanism angularly adjustable and longitudinally movable with respect to said guide, said cutting mechanism including a cutter movable in planes substantially parallel to the axis of adjustment of said cutting mechanism and offset therefrom, and a jack engaging said cutting mechanism for holding the same against angular movement when said cutter is in operation. 105
21. In a mining machine, the combination with cutting mechanism including a rotatable turret and a cutter bar mounted on said turret to swing in planes substantially parallel to the axis of rotation of said turret, said 110 cutter bar being offset from said axis, of a jack comprising two relatively extensible members, one of said members having means for engaging said turret between said cutter bar and axis, and the other of said members 115 having means for engaging the mine wall.
22. In a mining machine, the combination with cutting means, of guiding means for supporting said cutting means relative to which the latter is reciprocable during cut- 120
- 125
- 130

ting, said guiding supporting means being vertically movable and being angularly adjustable about a vertical axis and about a transverse horizontal axis.

23. In a mining machine, the combination with a guide, of cutting mechanism including a cutter bar angularly movable relative to a plurality of axes longitudinally movable in said guide during cutting and dis-
10 posable in one position thereof substantially wholly between the ends of the latter, said guide being vertically movable and being adjustable about a vertical axis.

24. In a mining machine, the combination with cutting mechanism including a pivoted cutter bar, of supporting means therefor including an element providing a guide along which said cutting mechanism is movable in lines parallel to the plane of said bar, adjustable supporting means for said element having provision for the vertical movement of the latter, and a fluid pressure operated ram for moving said element vertically, said supporting means for said element also comprising means permitting angular movement of said element upon the axis of said ram.

25. In a mining machine, in combination, a vertically movable guide, cutting mechanism movable in said guide and longitudinally of the latter during cutting, said cutting mechanism comprising a pivoted bar swingable in planes parallel to the major dimension of said guide, and a hydraulic motor for raising and lowering said guide 35 to permit said cutting mechanism to operate at different elevations.

26. In a mining machine, in combination, a vertically movable guide, cutting mechanism movable in said guide longitudinally thereof during cutting, said cutting mechanism being supported by said guide and being located beneath the same, and a hydraulic motor for raising and lowering said guide to permit said cutting mechanism to operate at different elevations.

27. In a mining machine, the combination with a pair of ways, of cutting mechanism movably mounted in said ways and including a cutting element carrying cutter bar swingable in a plane and about an axis perpendicular to the plane of said ways, and a motor for actuating said cutting elements, said cutting mechanism having at each end a pair of rollers engaging said ways respectively and supporting thereon the weight of said cutting mechanism and certain of said rollers constituting both propulsion members and supporting members.

28. In a mining machine, the combination with a pair of ways, of cutting mechanism movably mounted in said ways and suspended beneath the same, said cutting mechanism including a cutter and a motor for operating the same and having at each end a pair of rollers engaging said ways respec-

tively, certain of said rollers constituting propulsion members as well as supporting members.

29. In a mining machine, the combination with a pair of ways provided with racks, 70 of cutting mechanism movably mounted in said ways and including a cutter chain carrying pivoted cutter bar and a motor for operating the same, a pair of rollers engaging said ways respectively for supporting the forward end of said cutting mechanism, and a pair of pinions operated by said motor and engaging said racks respectively for supporting the rear end of said cutting mechanism and for moving the same longitudinally in said ways.

30. In a mining machine, in combination, guiding means, a cutter movable relative thereto, a turret by which said cutter is carried, said turret being rotatable about a substantially horizontal axis to permit said cutter to operate in different planes including a plane substantially coincident with the mine bottom, and means for supporting said turret at both ends on said guiding means. 90

31. In a mining machine, in combination, a guide, a cutter, a turret by which said cutter is carried, said turret being located beneath said guide and being rotatable about a substantially horizontal axis to permit said cutter to operate in different planes including a plane substantially coincident with the mine bottom, and means for supporting both ends of said turret from said guide. 100

32. In a mining machine, in combination, a pair of ways, cutting mechanism movably mounted in said ways and including a cutter, a motor for operating the same, a turret by which said cutter is carried, said turret being rotatable about a horizontal axis to permit said cutter to operate in different planes and being supported at its rear end by said motor, means engaging said ways for supporting said motor therefrom, and means engaging said ways for supporting the forward end of said turret cooperating directly with the latter.

33. In a mining machine, in combination, a swinging cutter bar, and means for supporting said cutter bar having provision for guiding the same for opposite bodily rectilinear movements during cutting and for adjusting the same vertically and also bodily angularly about a substantially horizontal longitudinally extending axis into a substantially horizontal or a vertical plane, said supporting means including a truck mounted guide disposable substantially against a working face and between whose sides said bar is disposable midway. 115

34. In a mining machine, in combination, a swinging cutter bar, and means for supporting said cutter bar having provision for guiding the same for opposite bodily rec- 120

- tilinear movements during cutting and for adjusting the same vertically and bodily angularly about a vertical axis and also bodily angularly about a substantially horizontal longitudinally extending axis into a substantially horizontal or a vertical plane, said supporting means including a truck mounted guide disposable substantially against a working face and between whose sides said bar is disposable midway.
35. In a mining machine, in combination, a swinging cutter bar, and means for supporting said cutter bar having provision for guiding the same for opposite bodily rectilinear movements during cutting and for adjusting the same vertically and also bodily angularly about a substantially horizontal longitudinally extending axis into a substantially horizontal or a vertical plane, said supporting means including a truck mounted guide disposable substantially against a working face and between whose sides said bar is disposable midway and said cutter bar being mounted to swing about an axis transverse to said horizontal longitudinally extending axis and having associated therewith a driving motor having a rotating element whose axis of rotation is parallel to the plane of the bar at all times.
36. In a mining machine, in combination, a swinging cutter bar, and means for supporting said cutter bar having provision for guiding the same for opposite bodily rectilinear movements during cutting and for adjusting the same vertically and also bodily angularly about a substantially horizontal longitudinally extending axis into a substantially horizontal or a vertical plane, said supporting means including a truck mounted guide disposable substantially against a working face and between whose sides said bar is disposable midway and said cutter bar being mounted to swing about an axis transverse to said horizontal longitudinally extending axis and being offset from the latter and having associated therewith a driving motor having a rotating element whose axis of rotation is parallel to the plane of the bar at all times.
37. In a mining machine, in combination, a bodily vertically movable guide and cutting mechanism longitudinally movable in said guide during cutting and disposable between the ends thereof when parallel to its path on said guide, said cutting mechanism including a cutter angularly adjustable about an axis extending longitudinally of said guide and adapted to act in different planes.
38. In a mining machine, in combination, a bodily vertically movable guide and cutting mechanism longitudinally movable in said guide during cutting and disposable between the ends thereof when parallel to its path on said guide, said cutting mech-
- anism including a cutter angularly adjustable about an axis extending longitudinally of said guide and adapted to act in different parallel planes.
39. In a mining machine, in combination, a bodily vertically movable guide, cutting mechanism movable in said guide longitudinally thereof during cutting, said cutting mechanism having provision for adjustment about an axis extending longitudinally of said guide and including a cutter bar offset from said axis whereby said cutter bar may be positioned beyond said guide at either side thereof, said cutter bar being mounted to swing about a second axis transverse to said first named axis and disposable to cut the plane of said guide between the sides of the latter.
40. In a mining machine, in combination, a bodily vertically movable guide, cutting mechanism longitudinally movable in said guide during cutting, said cutting mechanism including a cutter angularly adjustable about an axis extending longitudinally of said guide while the latter remains stationary, and means for tilting said guide about a transverse horizontal axis.
41. In a mining machine, in combination, cutting means including a pivoted cutter bar and means for supporting the same including a vertically movable support engageable with the face for support thereby, and a turret mounted on said support to turn about a substantially horizontal axis lying in a line disposed in fixed space relation to said face engaging supporting means.
42. In a mining machine, in combination, cutting means including a pivotally mounted cutter bar, and means for supporting the same including a vertically movable turret mounted to turn about a substantially horizontal axis, a second turret carried by said first named turret and movable about an axis transverse to said first named axis, and a support engageable with a working face for support thereby and movable with said first mentioned turret on vertical movement of the latter.
43. In a mining machine, in combination, a cutter, a vertically movable turret, said turret being rotatable about a substantially horizontal axis extending longitudinally of said machine, means for supporting said turret at both ends, and a second turret carried by said first named turret and by which said cutter is carried, said second turret being movable about an axis transverse to said first named axis.
44. In a mining apparatus, the combination with a truck having forwardly extending overhanging vertically and tiltingly adjustable guiding means, of supporting means carried at the forward end thereof and adapted to engage the face of material to be cut to support one end of the guid-

- ing means, and cutting mechanism including a motor and a cutting device reciprocable longitudinally along said guiding means and adapted to cut on either direction of movement thereof.
45. In a mining apparatus, a support, a kerf cutting mining machine mounted on said support and guided thereby for strictly rectilinear movement and including a cutter chain carrying cutter bar adapted to cut intersecting kerfs, and means for supporting said machine on the face of the material to be mined.
46. In a mining apparatus, a support, a kerf cutting mining machine mounted on said support and guided thereby for strictly rectilinear movement and including a cutter chain carrying cutter bar adapted to cut intersecting kerfs, and a plurality of spaced means for supporting said machine on the face of the material to be mined.
47. In a mining apparatus, a truck, substantially horizontal supporting means thereon adapted to contact with and be supported by the working face of the material to be mined, a kerf cutting mining machine thereon and movable bodily relative thereto during cutting of a plane kerf in the working face, and means for vertically adjusting one of said last two elements.
48. In a mining apparatus, a truck, substantially horizontal supporting means thereon adapted to contact with and be supported by the working face of the material to be mined, a kerf cutting mining machine thereon adapted to cut plane kerfs in the working face in planes parallel with said supporting means, and means for rotating one of said last two elements about a vertical axis.
49. In a mining apparatus, a truck, substantially horizontal supporting means thereon adapted to contact with and be supported by the working face of an entry, a kerf cutting mining machine thereon adapted to cut plane kerfs in the working face in planes parallel with said supporting means, and means for tilting and swinging the same about axes in intersecting planes.
50. In a mining apparatus, a support, a kerf cutting mining machine rotatively adjustable thereon about a vertical axis and including longitudinally disposed machine supporting means adjustable on said support about a horizontal transversely extending axis, said mining machine being adapted to cut a plane kerf in the working face in a plane parallel with said supporting means, and means for varying the elevation of said supporting means to permit cutting in parallel planes at different elevations.
51. In combination, a truck, an elongated pivoted guide member movable about a transverse axis thereon and wholly support-
- ed thereby, a pivoted frame supporting said member and movable about a vertical axis on said truck, said pivoted frame supporting the transverse pivot for said guide member, and a kerf cutting mining machine carried on said member and adapted to cut a plane kerf in the working face in a plane parallel with said guide member, said mining machine being movable bodily longitudinally therewith during cutting.
52. A mining machine comprising a wheeled truck, vertically adjustable guiding means supported thereon and engageable with the face for supporting thereby, and kerf cutting mechanism including a cutter bar movable relative to said guiding means and disposable substantially midway between the same or adapted to be fed for substantially its full length into a face while disposed at an angle to the path of movement.
53. A mining machine comprising a wheeled truck, a vertically adjustable guide supported thereon and engageable with the face for support thereby, kerf cutting mechanism including a cutter bar movable relative to said guide, and power operated means for elevating said guide mounted on said truck and relative to which said guide is vertically adjustable.
54. A mining machine comprising a wheeled truck, a vertically adjustable guide supported thereon and engageable with the face for support thereby, kerf cutting mechanism including a cutter bar movable relative to said guide, and motor driven means on said truck for selectively driving said truck or elevating said guide.
55. A mining machine comprising a wheel mounted truck, a guide tiltable about a horizontal axis thereon and supportable on the face, and kerf cutting mechanism movable longitudinally of said guide and disposable at will in a vertical or a horizontal plane.
56. A mining machine mechanism comprising a wheeled truck, guiding means thereon disposable at right angles to a face to be cut, kerf cutting mechanism movable under its own power longitudinally of said means and including a reciprocable motor and a pivotally mounted cutter chain carrying cutter bar movable in a plane, and means for adjusting said bar into vertical and horizontal planes including a horizontal plane in which the bar rests upon the mine bottom.
57. A mining machine mechanism comprising a wheeled truck, guiding means thereon disposable at right angles to a face to be cut, kerf cutting mechanism movable under its own power longitudinally of said means and including a pivotally mounted cutter chain carrying cutter bar movable in a plane and a motor actuating said bar and constituting the source of power for effecting longitudinal movement of the kerf cut-

- ting mechanism, and means for adjusting said bar into vertical and horizontal planes including a horizontal plane in which the bar rests upon the mine bottom and a higher parallel plane.
58. A mining machine comprising a wheel mounted truck, a guide tiltable about a horizontal axis thereon and supportable on the face, and kerf cutting mechanism including a pivoted cutter bar movable longitudinally of said guide and disposable at will in different vertical or different horizontal planes.
59. A mining machine comprising a wheel mounted truck, a guide swiveled on a vertical axis on said truck and tiltable about a horizontal axis thereon and supportable on the face, and kerf cutting mechanism movable longitudinally of said guide and disposable at will in vertical or horizontal planes.
60. A mining machine comprising a wheel mounted truck, a guide tiltable about a horizontal axis thereon and supportable on the face, motor driven kerf cutting mechanism movable longitudinally of said guide and disposable at will in vertical or horizontal planes, and motor driven mechanism on said truck propelling the latter.
61. A mining machine comprising a wheel mounted truck, a guide tiltable about a horizontal axis thereon and supportable on the face, motor driven kerf cutting mechanism movable longitudinally of said guide and disposable at will in vertical or horizontal planes, motor driven mechanism on said truck for propelling the latter, and means operatively connectible to said last mentioned mechanism for varying the elevation of said guide.
62. In a mining machine reciprocable toward and from a face in which a kerf is to be cut, a motor having an armature shaft, cutting mechanism including a swinging cutter bar actuated by one end of said armature shaft, a turret by which said cutter bar is carried, said turret being rotatable upon a horizontal axis to permit said cutter bar to operate in different planes and being rotatable by the other end of the armature shaft, and rack and pinion mechanism for moving said motor and cutting mechanism bodily longitudinally toward and from the face actuated by the last mentioned end of said armature shaft.
63. In a mining machine reciprocable toward and from a face in which a kerf is to be cut, a motor having an armature shaft, cutting mechanism including a swinging cutter bar actuated by one end of said armature shaft, a turret by which said cutter bar is carried, said turret being rotatable upon a horizontal axis parallel to the path of reciprocation of said machine to permit said cutter bar to operate in different planes and being rotatable by the other end of the armature shaft, and rack and pinion mechanism for moving said motor and cutting mechanism bodily longitudinally toward and from the face actuated by the last mentioned end of said armature shaft.
64. In a mining machine, a motor having a rotating element rotating on a horizontal axis, a plurality of gears coaxial with said axis spaced longitudinally thereof and rotated at equal angular rates by said motor, a turret arranged at one end of said motor and rotatable on a horizontal axis, a cutting mechanism supported on said turret and including a cutter bar pivotable on an axis perpendicular to the axis of rotation of said turret, an arcuate rack concentric with the axis about which the bar pivots and fixed relative to said bar, a shaft on said turret rotating on an axis parallel to said last mentioned axis and carrying a pinion meshing with said rack, and means for actuating said shaft to cause the same to swing said cutter bar including a plurality of parallel shafts rotatable by one of said gears at different angular rates, and means driven by the other of said gears for effecting bodily rectilinear feeding of said mining machine.
65. In a mining machine, a motor having a rotating element rotating on a horizontal axis, a plurality of gears coaxial with said axis spaced longitudinally thereof, and rotated at equal angular rates by said motor, a turret arranged at one end of said motor and rotatable on a horizontal axis, a cutting mechanism supported on said turret and including a cutter bar pivotable on an axis perpendicular to the axis of rotation of said turret, an arcuate rack concentric with the axis about which the bar pivots and fixed relative to said bar, a shaft on said turret rotating on an axis parallel to said last mentioned axis and carrying a pinion meshing with said rack, and means for actuating said shaft to cause the same to swing said cutter bar including a plurality of parallel shafts rotatable by one of said gears at different angular rates and disposed at opposite sides of said second mentioned axis, and means driven by the other of said gears for effecting bodily rectilinear feeding of said mining machine and rotation of said turret.
66. In a mining machine, the combination with a guide, of kerf cutting mechanism movable on said guide longitudinally thereof and including a swinging cutter chain carrying cutter bar and means for varying the plane of said bar relative to the plane of said guide, and means for supporting the forward end of said guide in the face being cut.
67. In a mining machine, the combination with a guide, of kerf cutting mechanism movable on said guide longitudinally thereof and including a swinging cutter chain carrying cutter bar located beneath the same

- and means for varying the plane of said bar relative to the plane of said guide, and means for supporting the forward end of said guide in the face being cut.
5. 68. In a mining machine, the combination with a guide, of kerf cutting mechanism movable on said guide longitudinally thereof and including a swinging cutter chain carrying cutter bar and means for varying the 10 plane of said bar relative to the plane of said guide, and means for supporting the forward end of said guide in the face being cut including a projecting portion on said guide adapted to engage a mine face.
15. 69. In a mining apparatus, a truck, a guideway, self-contained power operated cutting mechanism movable longitudinally along and upon said guideway, propulsion mechanism for said truck, hydraulic elevating mechanism for said guideway, and a common motor on said truck actuating said propulsion and elevating mechanisms.
20. 70. In a mining apparatus, a truck, a guideway, self-contained power operated cutting mechanism movable longitudinally along and upon said guideway, propulsion mechanism for said truck, hydraulic elevating mechanism for said guideway providing a pivot therefor, and a common motor on 25 said truck actuating said propulsion and elevating mechanisms.
25. 71. In a mining apparatus, a truck, self-contained power operated cutting mechanism supported thereon including rectilinear feeding means, propulsion mechanism for 30 said truck, hydraulic elevating mechanism for said cutting mechanism, and a common motor on said truck selectively operative to 35 actuate said elevating mechanism and said propulsion mechanism.
40. 72. In a mining apparatus, a truck, self-contained power operated cutting mechanism pivotally supported thereon including rectilinear feeding means, propulsion mechanism for 45 said truck, hydraulic elevating mechanism for said cutting mechanism, and a common motor on said truck selectively operative to 50 actuate said elevating mechanism and said propulsion mechanism.
50. 73. In a mining apparatus, a truck, self-contained power operated cutting mechanism pivotally supported thereon for adjustment about horizontal and vertical axes including rectilinear feeding means, propul- 55 sion mechanism for said truck, hydraulic elevating mechanism for said cutting mechanism, and a common motor on said truck selectively operative to 60 actuate said elevating mechanism and said propulsion mechanism.
60. 74. In a mining apparatus, a truck, self-contained power operated cutting mechanism adjustably supported thereon including a circulating cutter chain and rectilinear feeding means, hydraulic means on said 65 truck for adjusting said cutting mechanism, and a separate motor for actuating said hydraulic means.
75. 75. In a mining machine, the combination of a wheeled truck frame, a guiding frame swiveled thereon and having longitudinally extending guideways, said guiding frame being adjustable vertically relative to said truck frame, a machine body slidably mounted in said guideways, cutting mechanism carried by said body including a swingable cutter bar, and motor actuated devices for driving the wheels of said truck, for elevating said guiding frame relative to said truck frame, for swinging said cutter bar, and for moving said machine body in 80 said guideways.
80. 76. In a mining machine, the combination of a wheeled truck frame, a guiding frame swiveled thereon and adjustable vertically relative thereto, said guiding frame having longitudinally extending guideways, a machine body slidably mounted in said guideways, a motor carried within said body, cutting mechanism carried by said body including a swingable cutter bar, mechanism 85 driven by said motor for actuating said cutting mechanism and for swinging said bar and for moving the machine body in said guideways, and independent motor actuated mechanism for driving the wheels of said 90 truck and for elevating said guiding frame relative to said truck frame.
85. 77. In a mining machine, the combination of a wheeled support, a body pivotally mounted thereon, means for tilting said body 100 relative to said support, cutting mechanism carried by said body and including a rotatable cutter carrying head, motor driven mechanism for elevating said body relative to the supporting wheels, and motor driven 105 mechanism for actuating said cutting mechanism.
90. 78. In a mining machine, the combination of a wheeled support, a body pivotally mounted thereon, means for tilting said body 110 relative to said support, cutting mechanism carried by said body and including a rotatable cutter carrying head, motor driven mechanism for elevating said body relative to the supporting wheels, and motor driven 115 mechanism for actuating said cutting mechanism and for rotating said head.
95. 79. In a mining machine, the combination of a wheeled support, a body pivotally mounted thereon, means for tilting said body 120 relative to said support, a motor within said body, cutting mechanism carried by the forward end of said body and including a rotatable cutter carrying head, mechanism driven by said motor for actuating said 125 cutting mechanism, and motor driven mechanism for elevating said body relative to the supporting wheels.
100. 80. In a mining machine, the combination of a wheeled support, a body pivotally 130

- mounted thereon, means for tilting said body relative to said support, a motor within said body, cutting mechanism carried by the forward end of said body and including a rotatable cutter carrying head, mechanism driven by said motor for actuating said cutting mechanism and for rotating said head, and motor driven mechanism for elevating said body relative to the supporting 10 wheels.
81. In a mining machine, the combination of a wheeled truck frame, a guiding frame swiveled thereon for movement in a horizontal plane, said guiding frame also being tilttable about a horizontal axis and having longitudinally extending guideways, a machine body slidably mounted in said guideways, mechanism for elevating said guiding frame relative to said truck frame, cutting mechanism carried by said body including a cutter bar swingable in vertical and horizontal planes, and motor driven mechanisms for actuating the cutting mechanism and swinging said cutter bar, for driving the wheels of said truck, and for moving said body in said guideways.
82. In a mining machine, the combination with a wheeled support, a body pivotally mounted thereon, means for tilting said body relative to said support, a motor within said body, cutting mechanism carried by the forward end of said body and including a rotatable cutter carrying head, said head having a cutter bar pivotally mounted thereon, mechanism driven by said motor for rotating said head and for swinging said cutter bar, and motor driven mechanism for elevating said body relative to said supporting wheels.
83. In a mining machine, the combination with a wheeled support, a body pivotally mounted thereon, means for tilting said body relative to said support, a motor within said body, cutting mechanism carried by the forward end of said body and including a rotatable cutter carrying head, said head having a cutter bar pivotally mounted thereon, mechanism driven by said motor for rotating said head and for swinging said cutter bar, and a motor driven mechanism for elevating said body relative to said supporting wheels and for driving the supporting wheels.
84. In a mining apparatus, a truck, substantially horizontal supporting means thereon adapted to engage and be supported by the working face of the material to be mined and to transmit to the latter a portion of the weight of the mechanism supported by said means, a kerf cutting mining machine on said means adapted to cut a plane kerf in the working face in a plane parallel with said supporting means, and means for vertically adjusting one of said last two elements.
85. In a mining apparatus, a truck, substantially horizontal supporting means thereon adapted to engage and be supported by the working face of the material to be mined and to transmit to the latter a portion of the weight of the mechanism supported by said means, a kerf cutting mining machine on said means adapted to cut a plane kerf in the working face in a plane parallel with said supporting means, and means for rotating one of said last two elements about a vertical axis.
86. In a mining apparatus, a truck, substantially horizontal supporting means thereon adapted to engage and be supported by the working face of an entry and to transmit to the latter a portion of the weight of the mechanism supported by said means, a kerf cutting mining machine on said means adapted to cut a plane kerf in the working face, and means for tilting and swinging the same about axes in intersecting planes.
87. In a mining machine, a wheeled support, a tilttable body mounted thereon, means for tilting said body relative to the supporting wheels and for bodily elevating said body, a motor carried by said body, cutting mechanism including a cutter carrying head rotatably mounted on said body on a longitudinal axis, said head carrying kerf cutting means, and mechanism driven by said motor for actuating said kerf cutting means and for rotating said head about its axis.
88. In a mining machine, a wheeled support, a tilttable body mounted thereon, means for tilting said body relative to the supporting wheels and for bodily elevating said body, a motor carried by said body, cutting mechanism including a cutter carrying head rotatably mounted on said body on a longitudinal axis, said head carrying kerf cutting means, mechanism driven by said motor for actuating said kerf cutting means and for rotating said head about its axis, and motor driven means for propelling said wheeled support.
89. In a mining machine, a wheeled support, a tilttable body mounted thereon, means for tilting said body relative to the supporting wheels and for bodily elevating said body, a motor carried by said body, cutting mechanism including a cutter carrying head rotatably mounted on said body on a longitudinal axis, said head carrying pivoted kerf cutting means, and mechanism driven by said motor for actuating said kerf cutting means, for swinging said kerf cutting means about its pivot, and for rotating said head about its axis.
90. In a mining machine, a wheeled support, a tilttable body mounted thereon, means for tilting said body relative to the supporting wheels and for bodily elevating said body, a motor carried by said body, cutting mechanism including a cutter carrying head

- rotatably mounted on said body on a longitudinal axis, said head carrying pivoted kerf cutting means, mechanism driven by said motor for actuating said kerf cutting means, 5 for swinging said kerf cutting means about its pivot, and for rotating said head, and motor driven means for propelling said wheeled support.
91. In a mining machine, a wheeled support, a body mounted thereon for swiveling movement about a vertical axis and for tilting movement about a transverse axis, means for tilting said body relative to the supporting wheels and for bodily elevating said body, 10 a motor carried by said body, kerf cutting mechanism including a cutter carrying head rotatably mounted on said body on a longitudinal axis, said head carrying kerf cutting means, and mechanism driven by said motor 15 for actuating said kerf cutting means and for rotating said head about its axis.
92. In a mining machine, a wheeled support, a body mounted thereon for swiveling movement about a vertical axis and for tilting movement about a transverse axis, means for tilting said body relative to the supporting wheels and for bodily elevating said body, a motor carried by said body, kerf cutting mechanism including a cutter carrying head 20 rotatably mounted on said body on a longitudinal axis, said head carrying kerf cutting means, mechanism driven by said motor for actuating said kerf cutting means and for rotating said head about its axis, and motor 25 driven means for propelling said wheeled support.
93. In a mining machine, a wheeled support, a body mounted thereon for swiveling movement about a vertical axis and for tilting movement about a transverse axis, means for tilting said body relative to the supporting wheels and for bodily elevating said body, a motor carried by said body, kerf cutting mechanism including a cutter carrying head 30 rotatably mounted on said body on a longitudinal axis, said head carrying kerf cutting means, mechanism driven by said motor for actuating said kerf cutting means and for rotating said head about its axis, and motor 35 driven means for propelling said wheeled support.
94. In a mining machine, a wheeled support, a body mounted thereon for swiveling movement about a vertical axis and for tilting movement about a transverse axis, means for tilting said body relative to the supporting wheels and for bodily elevating said body, a motor carried by said body, kerf cutting mechanism including a cutter carrying head 40 rotatably mounted on said body on a longitudinal axis, said head carrying pivoted kerf cutting means, and mechanism driven by said motor for actuating said kerf cutting means, for swinging said kerf cutting means about its pivot, and for rotating said head about its axis.
95. In a mining machine, a wheeled support, a longitudinal guideway mounted thereon for tilting movement relative thereto, means for tilting said guideway relative to supporting wheels and for bodily elevating said guideway, a machine body slidably mounted on said guideway, a motor carried by said body, kerf cutting mechanism including a cutter carrying head mounted on said body for rotation about a longitudinal axis, said head carrying kerf cutting means, and means driven by said motor for actuating said kerf cutting means and for rotating said head about its axis.
96. In a mining machine, a wheeled support, a longitudinal guideway mounted thereon for tilting movement relative thereto, means for tilting said guideway relative to the supporting wheels and for bodily elevating said guideway, a machine body slidably mounted on said guideway, a motor carried by said body, kerf cutting mechanism including a cutter carrying head mounted on said body for rotation about a longitudinal axis, said head carrying kerf cutting means, and means driven by said motor for actuating said kerf cutting means, for rotating said head about its axis and for moving said body relative to said guideway.
97. In a mining machine, a wheeled support, a longitudinal guideway mounted thereon for tilting movement relative thereto, means for tilting said guideway relative to the supporting wheels and for bodily elevating said guideway, a machine body slidably mounted on said guideway, a motor carried by said body, kerf cutting mechanism including a cutter carrying head mounted on said body for rotation about a longitudinal axis, said head carrying kerf cutting means, means driven by said motor for actuating said kerf cutting means and for rotating said head about its axis, and motor driven means for propelling said wheeled support.
98. In a mining machine, a wheeled support, a longitudinal guideway mounted thereon for tilting movement relative thereto, means for tilting said guideway relative to the supporting wheels and for bodily elevating said guideway, a machine body slidably mounted on said guideway, a motor carried by said body, kerf cutting mechanism including a cutter carrying head mounted on said body for rotation about a longitudinal axis, said head carrying pivoted kerf cutting means, and means driven by said motor for actuating said kerf cutting means, for swinging said kerf cutting means about its pivot, and for rotating said head about its axis.
99. In a mining machine, a wheeled sup-

- port, a longitudinal guideway mounted thereon for tilting movement relative thereto, means for tilting said guideway relative to the supporting wheels and for bodily elevating said guideway, a machine body slidably mounted on said guideway, a motor carried by said body, kerf cutting mechanism including a cutter carrying head mounted on said body for rotation about a longitudinal axis, said head carrying pivoted kerf cutting means, and means driven by said motor for actuating said kerf cutting means, for swinging said kerf cutting means about its pivot, for rotating said head about its axis, and for moving said body relative to said guideway.
100. In a mining machine, a wheeled support, a frame member pivotally connected with said support to rock on a transverse axis, a second frame member pivotally connected to said first frame member at the front end thereof to rock on a longitudinal axis, kerf cutting mechanism mounted on said second frame member and having angular movement with respect thereto, said kerf cutting mechanism including an elongated plane cutter bar carrying an orbitally movable cutter chain, and means for lowering and raising said cutting mechanism vertically relative to said wheeled support.
101. In a mining machine, a wheeled support, a motor thereon, driving connections between said motor and the support wheels, a frame member mounted on said support for tilting movement upon a transverse axis relative to the support wheels, a second frame member pivotally connected to the first frame member to rock on a longitudinal axis, kerf cutting mechanism carried by said second frame member and having angular movement with respect thereto, said cutting mechanism including an elongated plane cutter bar carrying an orbitally movable cutter chain, a second motor carried on said support for driving and angularly moving said cutting mechanism, and motor driven mechanism for elevating said cutting mechanism vertically relative to said wheeled support.
102. In a mining machine, a wheeled support, a motor thereon, driving connections between said motor and the wheels, a frame member mounted on said support for movement upon a transverse axis relative to the support wheels, a second frame member piv-
- otally connected to the first frame member to rock on a longitudinal axis, kerf cutting mechanism carried by said second frame member and having angular movement with respect thereto, said cutting mechanism including an elongated plane cutter bar carrying an orbitally movable cutter chain, a second motor carried on said support for driving and angularly moving said cutting mechanism, motor driven mechanism for raising and lowering said cutting mechanism vertically relative to said wheeled support, and motor driven mechanism for elevating said cutting mechanism vertically relative to said wheeled support.
103. In a mining machine, a wheeled support, a motor thereon, driving connections between said motor and the support wheels, a frame member adjustably mounted on said support, means operated by said motor for vertically elevating said frame member relative to said wheeled support, a second frame member pivotally connected to said first frame member to rock on a longitudinal axis, and kerf cutting mechanism carried by said second frame member and having angular movement with respect thereto, said kerf cutting mechanism including an elongated plane cutter bar carrying an orbitally movable cutter chain and mechanism for tilting said cutting mechanism about a transverse axis relative to said wheeled support to change the angle of said cutter bar.
104. In a mining machine, a wheeled support, a motor thereon, driving connections between said motor and the support wheels, a frame member adjustably mounted on said support, hydraulic means including a pump driven by said motor and a cylinder and piston device operated by said pump for vertically elevating said frame member relative to said wheeled support, a second frame member pivotally connected to said first frame member to rock on a longitudinal axis, kerf cutting mechanism carried by said second member and having angular movement with respect thereto, said kerf cutting mechanism including an elongated plane cutter bar carrying an orbitally movable cutter chain, and mechanism for tilting said cutting mechanism about a transverse axis relative to said wheeled support to change the angle of said cutter bar.

In testimony whereof I affix my signature.
FRANK CARTLIDGE.
